(57) **CLAIM**

The ornamental design for a high density multimedia interface connector, as shown and described.

DESCRIPTION

FIG. 1 is a front and a lower right perspective view of a high density multimedia interface connector showing our new design;

FIG. 2 is a top view of the high density multimedia interface connector shown in FIG. 1;

FIG. 3 is a bottom view of the high density multimedia interface connector shown in FIG. 1;

FIG. 4 is a front view of the high density multimedia interface connector shown in FIG. 1;

FIG. 5 is a rear view of the high density multimedia interface connector shown in FIG. 1;

FIG. 6 is a left side view of the high density multimedia interface connector shown in FIG. 1; and,

FIG. 7 is a right side view of the high density multimedia interface connector shown in FIG. 1.
